UNITED STATES PATENT OFFICE.

HARRY C. LA FLAMBOY, OF DETROIT, MICHIGAN, ASSIGNOR OF TWO-THIRDS
TO ROBERT THUNER AND BETHUNE DUFFIELD, OF DETROIT, MICHIGAN.

MATCH-BOX-MAKING MACHINE.

SPECIFICATION forming part of Letters Patent No. 718,480, dated January 13, 1903.

Application filed April 12, 1902. Serial No. 102,501. (No model.)

To all whom it may concern:

Be it known that I, HARRY C. LA FLAMBOY, a citizen of the United States, residing at Detroit, county of Wayne, State of Michigan, have invented certain new and useful Improvements in Match-Box-Making Machines; and I declare the following to be a full, clear, and exact description of the invention, such as will enable others skilled in the art to which it 5 pertains to make and use the same, reference being had to the accompanying drawings, which form a part of this specification.

My invention relates to match-box-making machines; and it consists in the improvements hereinafter described, and pointed out 15 in the claims.

Referring to the accompanying drawings, Figure 1 is a side elevation, partly broken away to show its internal construction, of a 20 machine embodying my invention. Fig. 2 is a sectional elevation of the same, the section being taken on the line 2 2, Fig. 1, the left-hand portion being shown. Fig. 3 is an enlarged detail view showing the left-hand end 25 of the machine as shown in Fig. 1. Fig. 4 is an elevation showing the right-hand end of the machine as shown in Fig. 1. Fig. 5 is a plan view of the machine, a portion being broken away at the right to economize room.

30 Fig. 6 is a perspective view of the box formed upon the machine. Fig. 7 is a plan view showing the blank from which the box is made and illustrating the manner of cutting the paper to form the blanks. Fig. 8 is a perspective view of the box-forming frame. Fig. 35 9 is a section in the plane indicated by the lines 9 9, Fig. 8. Fig. 10 is a section in the plane indicated by the line 10 10, Fig. 8. Fig. 11 is a plan view of two of the box-forming 40 frames connected together and constituting two links of the chain, together with some of the then adjacent parts of the machine, illustrating the method of turning the end flaps of the side-forming part of the blank inward. Fig. 45 12 is a plan view of two of the box-forming frames connected together and constituting two links of the chain, together with some of the then adjacent parts of the machine, illustrating the method of turning up the end- 50 forming part of the blank. Fig. 13 is a de-

tail view of the blank-cutting knife and part of the table.

Referring to Fig. 7, the blank is an oblong rectangular piece of paper having at its ends slits a' a' a' a' the height of the ends of the 55 box and located a distance from the side edges of the blank equal to the height of the sides of the box. Lines joining the inner ends of said slits, the cross-lines being extended to the lateral edges of the blank, divide the 60 blank up into nine parts, which are described as follows: A is the bottom-forming part of the blank. A' A' are the side-forming parts of the blank. A² A² A² A² are end flaps upon the parts A' A'. A³ A³ are the end-forming 65 parts of the blank.

Referring to Fig. 6, the box is formed from the above-described blank in the following manner: A little glue is placed upon the inside of the end-forming portions of the blank, 70 toward the ends thereof, as indicated by the shaded portions a³, Fig. 7. Each of the parts A' A', together with its end flaps A² A², is then turned up into a vertical plane. The end flaps A² A² are then turned inward into planes 75 at right angles to the parts A' A'. Now the end-forming portions A³ A³ are turned upward, bringing the glue a³ a³ a³ a³ against the outside of the flaps A² A² A² A², and thereby 80 securing the various parts in their proper relative positions, as illustrated in Fig. 6.

The box-forming frame B is illustrated in detail in Figs. 8, 9, and 10, in which B' is an oblong rectangular frame the opening through which is of the width of the box to be 85 formed and of a length equal to or slightly exceeding the length of the blank from which the box is formed. B⁶ B⁶ are two flanges of about the length of the box and of a width about equal to the depth of the box. The 90 flanges B⁶ extend downward from the edges of the opening of the frame B', so that their inner surfaces are in line with said edges. The ends of the flanges B⁶ are at a distance from the ends of the opening through the 95 frame B' equal to or a little greater than the length of the flaps A². B² is an overhanging tongue secured at one end to the frame B', extending upward, then turning parallel to the plane of said frame, and extending above 100

the center of the same. B³ is a block of the size of the interior of the box to be formed, around which block the box is formed. The block B³ acts, in connection with the frame 5 B' and flanges B⁶, as a die to bend up the side pieces A' of the blank. B⁴ is a rod rising from the center of the block B³ and extending through an aperture in the tongue B². B⁵ is a roller pivoted upon a horizontal axis at 10 the top of the rod B⁴. B⁸ is a tension coil-spring, acting to lift the block B³ to the upper limit of its travel. B⁷ indicates hinges by which the different frames B may be connected together. C' is a chain made up of a large 15 number of frames B, hinged together, with their longer edges toward each other. C C are rollers having polygonal peripheries mounted so as to turn upon shafts C⁵, mounted in a suitable framework. C² C², Figs. 1 and 4, 20 are disks located upon opposite sides of one of the drums C upon the shaft C⁵ and adapted to be driven by the turning of said shaft. C⁴ indicates lugs extending laterally from the chain C'. C³ indicates cam-teeth extending from the 25 peripheries of the disks C² and adapted to engage the lugs C⁴ to move the chain C' intermittently. F is a presser-plate adapted to press a large number of blocks B³ into their openings in the frame B'. The plate F is located 30 above a portion of the chain C' and is secured to the guided and vertically-reciprocating arms F² F². F³ F³ are springs acting to press the arms F² F², and consequently the plate F, to the upper limit of their travel. F⁴ is a horizontal shaft resting in bearing upon standards 35 above the arms F² F². F¹⁰ indicates cams upon the shaft F⁴, adapted to contact a cam-surface on the top of the rods F² to drive said rods downward. F⁶ is a pulley upon the shaft F⁴. 40 F⁶ is a bevel gear-wheel upon the end of the shaft F⁴. F⁸ is a vertical shaft extending at right angles to the shaft F⁴. F⁷ is a conical gear-wheel upon the upper end of the shaft F⁸, gearing with the wheel F⁶. The lower 45 end of the vertical shaft F⁸ is geared to the shaft C⁵, so that the rotation of the former shall be communicated to the latter. D⁴ is a bevel gear-wheel upon the end of the shaft C⁵. D⁶ is a horizontal shaft extending at right 50 angles to the shaft C⁵. D⁵ is a bevel gear-wheel on the end of the shaft D⁶, gearing with the wheel D⁴. D⁷ is a bevel gear-wheel on the end of the shaft D⁶. D³ is a vertical shaft having a bevel gear-wheel D⁸ upon its lower 55 end which engages the bevel gear-wheel D⁷. D² is a wiping-cam upon the shaft D³, the function of which is to press in the flanges A², as hereinafter described. There is a corresponding shaft and wiper, like D² and D³, 60 located behind the same. D is a flange extending around the frame by the side of the chain upon each side of the chain and adapted, as hereinafter described, to hold the flaps A² against the end of the block B³. 65 Having described the mechanism for folding the blank to form the box, I will now describe its operation. The cut blanks are

placed upon the upper surfaces of the frames B', as hereinafter described, with the part A, which forms the bottom of the box, and also 70 the parts A³ A³, which form the ends of the same, above the opening through said frame, and the parts A' A', which form the sides of the box, lying upon said frame and supporting the blank. The presser-plate F is now 75 depressed by means of the cams F¹⁰ F¹⁰ acting upon the cam-surfaces at the top of the rods F² F². The plate F strikes against the friction-rollers B⁵ at the tops of the rods B⁴ and forces the blocks B³ down into the opening through the frame B' and between the flanges B⁶, thus turning the sides A' up between said flanges and block and turning the flaps A² so that they extend beyond the block B³ in the same plane as the sides A'. Cams 80 C⁸ now engage lugs C⁴ upon the chain C', forcing said chain along. H is a flange lying parallel to the chain C', around said chain and a distance therefrom equal to that of the top of the roller B⁵ when the block B³ is depressed. 85 When the chain C' is moved along, as above described, the frames B, which are under the presser-plate F, with their blocks B³ depressed with the blanks under them, are moved from under said plate and under the flange H, which holds said blocks down. As the flaps A², which are in advance, come in contact with the flanges D in inwardly-beveled ends of said flanges, Fig. 11, press said flaps inward 90 against the ends of the blocks B³. At or about 95 this time the wiper-cams D² D² press the following flaps forward and inward against the end of the block B³, and as said block moves along all the flaps pass under the flanges D and are held in place thereby. As the box-forming frames move along they pass by the end of a flange E, which has a warped surface formed on its end adapted to turn up the ends A³ A³ of the box. When the ends of the box are turned up, the glue a³ a³ a³ a³ come 100 against the flaps A² A² A² A² and secure the two in place, and therefore the box, into its proper form, as shown in Fig. 6.

The method of forming the blanks and feeding them to the machine is described as follows, particular reference being had to Fig. 2: The stiff paper or pasteboard J in the roll is placed upon a shaft upon the frame of the machine. It is then led over a roller J¹ and under and around a roller J², then between 110 rollers J³ J³, and upon the table T. J¹² is a trough containing glue or paste. J¹¹ is a roller provided with radially-extending brushes j¹¹ at its periphery. Said brushes dip into the glue in the trough J¹² and come in contact 115 with the paper as it passes under the roller J², applying patches of glue a³ a³ a³ a³, Fig. 7, to its surface. J⁴ J⁵ are rollers between which the paper j passes. The roller J⁵ is partly cut away at j⁵, so that the rollers J⁴ J⁵ drive the 120 paper which passes between them intermittently. J⁶ J⁷ are a pair of rollers entirely 125 similar to J⁴ J⁵, except that they are provided with circular cutting-knives extending

around their circumferences, said knives being spaced from each other a distance equal to the width of the blanks for the boxes. F^{11} is a sprocket-wheel upon the shaft F^4 . From the wheel F^{11} extends the sprocket-chain K , which passes over and engages with a sprocket-wheel K' , Fig. 5, upon the same shaft with the roller J^7 . The motion of the roller J^7 is communicated to the roller J^3 J^5 by means of the shaft K^5 and bevel-wheels K^4 K^6 K^7 K^8 K^9 . The shaft K^5 is supported upon the frame of the machine in bearings K^{10} K^{10} . The roller J^{11} is driven by sprocket-wheels K^{11} K^{12} and sprocket-chain K^{12} from the roller J^3 . J^{10} is an arm secured to the presser-plate F and extending over the roller J^7 . J^9 is a knife on the free end of the arm J^{10} . The knife J^9 reciprocates with the presser-plate F and acts to cut the paper across at right angles to its length at intervals equal to the length of the blanks. The knife J^9 is provided with smaller knives j^9 , which extend at right angles to the main knife from each side thereof and opposite each other. The knives j^9 are adapted to cut the slits a' , Fig. 7, in the blank. When the machine is set in motion, the paper begins to feed off from the roll, passing around the pulley J^2 , and, receiving the glue, it then passes between the rollers J^3 , by which it is moved forward at a uniform speed. From the roller J^3 the paper extends over a convexity in the table to the rollers J^4 J^5 , by which it is also carried forward at the same speed as the rollers J^3 , except when the cutting-knife J^9 is down, during which time the cut-away portion of the roll J^3 is opposite the roll J^4 and the paper remains still. During this time the paper bows upward, as at j , Fig. 2. After having passed the knife J^9 the paper passes between the rolls J^6 J^7 and is cut by the knives upon the upper roller. The blanks are now formed as shown in Fig. 7, and they are passed between the guide-plates J^{13} upon the frames B' at the end of the table T and beneath the presser-plate F . After being thus placed in position upon the frames B' they are formed up into boxes, as above described. The flange H turns up at h and is discontinuous to h' . Between these two points the blocks B^8 are free to rise under the impulse of their springs B^8 . The flange H at h' is formed to extend over the top of the pulleys B^5 in their most elevated position and to act as a cam-surface to depress said rollers until they pass under the plate F at the lower portion of the stroke of said plate. M is a stationary cam adapted to engage the edges of the ends of the box and draw them from the block. When each box is removed from the block B^8 , it drops into the trough G , and is thereby conveyed to a convenient receptacle. The rollers which feed the paper are grooved so that they shall not come in contact with the glue upon the paper. It will be observed that no preliminary preparation of the paper from which the blanks are made is necessary, but that the pa-

per is placed upon the machine in its commercial form. It will also be noticed that a number of blanks are fed to the machine at once and that the sides of an equal number of blanks are turned up at one operation.

The shaping of the box from the blank has to be gradual in order to avoid tearing the paper. By performing the principal shaping operation upon a number of blanks at once I am enabled to save considerable time and increase the output of the machine.

What I claim is—

1. In a box-making machine, an endless chain consisting of a plurality of links pivoted together, each of said links being provided with both a forming-frame and a forming-block, said block being movable with reference to said frame so as to engage said frame and turn up the sides of the blank and hold said blank in said frame with the ends of the sides protruding, means for actuating said chain, a flange extending along the side of said chain next to the end of said block, said flange being so located and so formed that it shall act to press a leading end of the side of the box inward and so that it shall prevent a bent-in end of the side of a box that has passed under it from bending outward, and means for bending inward the following end of the side and passing it under said flange.

2. In a box-making machine, an endless chain consisting of a plurality of links pivoted together, each of said links being provided with both a forming-frame and a forming-block, said block being movable with reference to said frame so as to engage said frame and turn up the sides of the blank and hold said blank in said frame with the ends of the sides protruding, means for actuating said chain, a flange extending along the side of said chain next to the end of said block, said flange being so located and so formed that it shall act to press a leading end of the side of the box inward and so that it shall prevent a bent-in end of a side of the box that has passed under it from bending outward, and a wiper-cam adapted to contact a following end of the side of the box and pass it under said flange.

3. In a box-making machine, an endless chain consisting of a plurality of links pivoted together, each of said links being provided with both a forming-frame and a forming-block, said block being movable with reference to said frame so as to engage said frame and turn up the sides of the blank and hold said blank in said frame with the ends of the side-forming portions of the blank protruding, means for actuating said chain, a flange extending along the side of said chain next to said block, said flange being so located and so formed that it shall act to press a leading end of the side of the box inward, and so that it shall prevent a bent-in end of a side of the box that has passed under it from bending outward, and means for bend-

ing inward a following end of the part of the blank that forms the side of the box, and passing said end under said flange, and a second flange similarly located to said first - mentioned flange and having its end so formed as to contact and turn up into position the box-end-forming portion of the blank.

4. In a box-forming machine, the combination of an endless chain made up of a plurality of links, the several links having the dies and matrices of a box-forming machine upon them, a feeding apparatus adapted to receive a roll of paper of the usual width, means for cutting said paper transversely in

blanks, and feeding the blanks cut out of one width at one time to said links, means for giving said chain an intermittent motion a distance equal to the width of said paper, and means for causing the dies of all the links passing one point at one motion of the chain to engage their matrices.

In testimony whereof I sign this specification in the presence of two witnesses.

HARRY C. LA FLAMBOY.
